CLAIM

The ornamental design for a switch lever for an automotive vehicle, as shown and described.

DESCRIPTION

FIG. 1 is a perspective view of a switch lever for an automotive vehicle according to an embodiment of the invention.

FIG. 2 is a front view of the switch lever for an automotive vehicle according to the embodiment of FIG. 1.

FIG. 3 is a back view of the switch lever for an automotive vehicle according to the embodiment of FIG. 1.

FIG. 4 is a left view of the switch lever for an automotive vehicle according to the embodiment of FIG. 1.

FIG. 5 is a right view of the switch lever for an automotive vehicle according to the embodiment of FIG. 1.

FIG. 6 is a top view of the switch lever for an automotive vehicle according to the embodiment of FIG. 1; and,

FIG. 7 is a bottom view of the switch lever for an automotive vehicle according to the embodiment of FIG. 1.

The portions in broken lines are for illustrative purposes only and form no part of the claimed design.
